CLAIM

The ornamental design for a chair, as shown and described.

DESCRIPTION

FIG. 1 is a front view of the chair;
FIG. 2 is a side view of the chair of FIG. 1, the other side of the chair being the mirror image of this view;
FIG. 3 is a top plan view of the chair of FIG. 1; and,
FIG. 4 is a rear view of the chair of FIG. 1.
The portion of the chair shown in broken lines has been shown for illustration purposes only and does not form part of the design.
